UNITED STATES PATENT OFFICE.

KALIL BEETAR, OF NEW YORK, N. Y.

DESIGN FOR A ROSARY-BRACELET.

40,321.

Specification for Design.

Patented Oct. 26, 1909.

Application filed June 29, 1909. Serial No. 505,087. Term of patent 14 years.

To all whom it may concern:

Be it known that I, KALIL BEETAR, a subject of the Sultan of Turkey, and resident of the borough of Manhattan, city, county, and State of New York, have invented a new, original, and ornamental Design for a Rosary-Bracelet, of which the following is a specification.

Reference is to be had to the accompanying drawing which shows a face view of a rosary bracelet embodying my new design.

The new design comprises beads strung on a coiled wire in the form of a bracelet and in proper sequence to form a rosary. Each bead is surmounted by gold or other metallic caps located on each bead at di-

ametrically opposite points and surrounding the wire. The ends of the coiled wire are formed with spheres to maintain the beads in position. A chain has its one end connected with the one end of the coiled wire and its other end connected with the wire between the fourth and fifth beads from the other end of said wire.

I claim—

The ornamental design for a rosary bracelet as shown and described.

KALIL BEETAR.
